UNITED STATES PATENT OFFICE

126,434

DESIGN FOR A NECKTIE

George W. French, Chicago, Ill.

Application August 16, 1940, Serial No. 94,448

Term of patent 7 years

To all whom it may concern:

Be it known that I, George W. French, a citizen of the United States, residing at Chicago, in the county of Cook and State of Illinois, have invented a new, original, and ornamental Design for a Necktie, of which the following is a specification, reference being had to the accompanying drawing, forming a part thereof.

In the drawing:

Fig. 1 is a view in elevation of a necktie embodying my design showing in dotted lines the retaining flaps in unfolded position; and

Fig. 2 is a side elevation of the same.

I claim:

The ornamental design for a necktie, as shown.

GEORGE W. FRENCH.
